UNITED STATES PATENT OFFICE.

WILLIAM MANNING BRADLEY, OF LOS ANGELES, CALIFORNIA.

DESIGN FOR A LAMP.

60,605.

Specification for Design.

Patented Mar. 14, 1922.

Application filed June 14, 1921. Serial No. 477,557. Term of patent 3½ years.

To all whom it may concern:

Be it known that I, WILLIAM MANNING BRADLEY, a citizen of the United States, residing at Los Angeles, in the county of Los Angeles and State of California, have invented a new, original, and ornamental Design for a Lamp, of which the following is a specification, reference being had to the accompanying drawings, forming part thereof, in which the figure is a perspective view of the lamp showing my new design.

I claim:—

The ornamental design for a lamp as shown.

WILLIAM MANNING BRADLEY.
